UNITED STATES PATENT OFFICE.

PETER F. SCHNEIDER, OF DETROIT, MICHIGAN.

AGITATOR FOR WASHING MACHINES.

Application filed April 23, 1921. Serial No. 463,985.

To all whom it may concern:

Be it known that I, PETER F. SCHNEIDER, a citizen of the United States, residing at Detroit, county of Wayne, State of Michigan, have invented a certain new and useful Improvement in Agitators for Washing Machines, and declare the following to be a full, clear, and exact description of the same, such as will enable others skilled in the art to which it pertains to make and use the same, reference being had to the accompanying drawings, which form a part of this specification.

This invention relates to agitators for washing machines and the object of the invention is to provide an agitator of the character described adapted to be reciprocated vertically within a tub to cause agitation of the water and clothing therein. A further object of the invention is to provide an agitator of the character described which is so formed as to contain a quantity of air sufficient to at least partially float the same in water whereby subsequent to movement into the water the agitator tends to rise and float due to the air contained therewithin. A further object of the invention is to provide an agitator of the character described adapted upon downward movement to deflect the water and clothing from the edges of the tub toward the center thereof and upon upward movement to reverse the said action of the water and clothing. A novel feature of the invention is involved in the construction of the upper flange which upon downward movement is adapted to deflect the water and clothing downward and toward the center of the tub and also in the construction of the lower flange which upon downward movement is adapted to deflect the water and clothing upward and toward the center of the tub, this movement of the water and clothing by the two flanges causing excessive agitation. These objects and the several novel features of the invention are hereinafter more fully described and claimed and the preferred form of construction by which these objects are attained is shown in the accompanying drawings in which—

Fig. 1 is a section through a tub and agitator embodying my invention.

Fig. 2 is a plan view of the agitator showing the cross arm of the agitator secured to the upper end of the vertically reciprocable shaft.

Fig. 3 is an enlarged view of the means for securing the cross arm of the agitator to the vertically reciprocable shaft.

Fig. 4 is a section through an alternative form of agitator.

I preferably use a cylindrical tub 1 of sheet metal or the like having a vertical central shaft 2 therewithin adapted to be vertically reciprocated by a mechanism contained in the casing 3 which is not a part of this invention. The shaft 2 at the upper end is provided with an aperture 4 therethrough as shown in dotted lines in Figs. 1 and 3. The agitator 5 is provided with a yoke 6 channel shaped in cross section, the said yoke being apertured to receive the upper end of the shaft 2. The yoke is provided with a bearing portion 7 about the shaft and with a wall 8 connecting the opposite sides thereof as shown more particularly in Figs. 1 and 3. The yoke is provided with bifurcated ends consisting of two arms 9 and 10 and between these two arms at one end of the yoke is a knob 11, as shown more particularly in Fig. 3, the knob being connected to a pin 12 which extends through the wall 8, bearing portion 7, and through the aperture 4 in the upper end of the shaft 2. A coiled spring 13 is provided about the rod 12 and forces against the wall 8 at one end and against the washer 14 at the opposite end, which is secured to the shaft by a pin, thus holding the rod in position in the said aperture 4. The arms 9 and 10 are each provided with a foot portion 15 shaped to conform to the upper surface of the flange 17 of the agitator and a piece of stiff metal 16, shown more particularly in Figs. 1 and 3, is shaped to conform to the shape of the under side of the flange 17 and extends slightly beyond the feet 15, as shown in dotted lines in Fig. 3. A series of bolts or rivets 18 are then passed through the feet 15, through the flange 17 and through the metal strips 16 thus securing the said three parts together and preventing the rivets from tearing through the flange 17 during reciprocation of the agitator. The agitator 5, as shown in Fig. 1, is preferably formed of sheet metal and is cylindrical in shape having an inturned flange 17 at the upper edge which is curved downwardly and provided with a rolled edge 19 so as not to catch on the clothes during washing thereof. At the lower end of the cylindri-

cal agitator 5 I provide a substantially V shaped annular portion 20 which is provided with an annular flange 21 adapted to be welded, riveted or otherwise secured 5 to the inner face of the agitator 5, thereby forming an airtight annular chamber 22 which tends to float the agitator in the water in the tub.

In operation the tub is filled with water 10 and clothing to about the point of the V shaped member, shown in Fig. 1, whereupon the shaft and agitator are vertically reciprocated by the driving mechanism beneath the tub. As the agitator is moved 15 downwardly the curved face 24 of the V shaped member deflects the water and clothing upwardly and toward the center thereby preventing the clothing from passing into the space 25 between the agitator and the 20 wall of the tub. As the agitator is further moved downwardly the flange 17 is forced into the water which deflects the water and clothing downwardly and toward the center, the movements of the water and clothing 25 by the flange 17 and member 20 converging toward the center and causing an extreme agitation thereof thereby washing the clothes quickly and thoroughly. The water in the tub is preferably of sufficient depth 30 to allow the complete agitator to be submerged in its lowest position and the air contained in the compartment 23 will tend to cause the agitator to move upwardly through the water from its lowest position 35 to a floating position thereby relieving the driving mechanism to some extent in raising the agitator. Upon upward movement of the agitator the water and clothes are again deflected toward the center by the 40 shape of the upper face of the flange 17 and the face 26 of the V shaped member, the said movement giving the water a downward whirling action. When the clothes are completely washed the operator, by pulling the 45 knob 11 to the left, may withdraw the rod 12 from the aperture 4 in the shaft end against the tension of the spring 13 at which time the agitator may be easily lifted from the tub to allow the clothes to be handled 50 and passed through a wringer (not here shown). A pair of lugs 37 are provided extending inwardly from opposite sides of the channel shaped yoke as shown in dotted lines in Fig. 3, so that upon withdrawal of 55 the rod 12 the washer 14 strikes the said lugs and limits outward movement thereof. It is to be particularly noted that when the agitator is withdrawn from the tub the water will drain from the curved flange 60 17 and from the beveled face 26 of the V shaped member 20 so that no water or clothing is withdrawn from the tub upon withdrawal of the agitator. As shown in Fig. 65 4, the V shaped annular member 20 may be made a separate piece from the agitator 5

and secured thereto. For this purpose a flange 27 is provided which may be welded or riveted to the wall 28 of the agitator 5 on either the outside or inside, the outside as shown being preferable in order to cover 70 the lower edge of the wall 28 and thus present a smooth surface to come in contact with the clothes.

From the foregoing description it becomes evident that the device is of somewhat 75 simple construction, is of comparatively low manufacturing cost and provides an agitator for washing machines which causes extreme agitation of the water thereby washing the clothes very thoroughly and in the shortest 80 possible time and which accomplishes the objects desired.

Having thus fully described my invention, its utility and mode of operation, what 85 I claim and desire to secure by Letters Pat- 90 ent of the United States is—

1. The combination in a washing machine of a tub having a vertically reciprocable shaft therein, an agitator secured to the said shaft consisting of a cylindrical member 95 having an inturned upper flange curved downwardly and toward the center thereof, and a substantially V shaped annular member secured to the lower edge of the agitator.

2. The combination in a washing machine 95 of a tub having a central shaft vertically reciprocable therewithin, an agitator secured to the said shaft consisting of a cylindrical part having an inturned downwardly curved flange at its upper edge and 100 an annular member substantially V shaped in cross section, the edges of the annular member being secured in spaced relation to the wall of the agitator at the lower edge thereof.

3. The combination in a washing machine, of a tub having a shaft vertically reciprocable therewithin, a cylindrical agitator provided with an inwardly extending flange 110 at the upper edge and a yoke extending across and secured at each end to the said flange and being also provided with a central aperture therein to receive the shaft, the shaft being provided with an aperture through the upper end thereof, a spring 115 pressed rod carried by the said yoke and adapted to extend through the aperture in the shaft, and an annular member substantially V shaped in cross section secured to the cylindrical wall of the agitator.

4. The combination in a washing machine of a tub having a vertically reciprocable shaft therewithin, a cylindrical agitator secured to the said shaft having an inturned upper flange curved downward and toward the center thereof, a substantially V shaped annular member secured to the agitator adjacent the lower edge, the lower face of the V shaped member being arcuate in cross section.

5. The combination in a washing machine having a vertically reciprocable shaft therewithin, a cylindrical agitator secured to the said shaft and a substantially V shaped annular member secured to the agitator adjacent the lower edge, the lower face of the V shaped member being arcuate in cross section.
6. In a washing machine, a tub, a cylindrical agitator reciprocably mounted therewithin having an inturned upper flange and a V shaped annular flange adjacent the lower edge, and means for reciprocating the agitator.
7. The combination in a washing machine, of a tub having a shaft vertically reciprocable therewithin, a cylindrical agitator, a yoke extending across the agitator and provided with bifurcated ends secured to the agitator, the yoke being provided with a central aperture to receive the shaft, the shaft being provided with an aperture through the upper end thereof, a rod extending longitudinally of the yoke and carried thereby, the end of the rod extending through the aperture in the shaft, a spring normally holding the rod in position in the aperture in the shaft and a knob positioned between the bifurcation at one end of the yoke for withdrawing the rod from the shaft against the tension of the spring.
8. In a washing machine, a tub, a cylindrical agitator reciprocably mounted therewithin, an inwardly extending substantially V shaped annular member secured to the agitator adjacent the lower edge providing a sealed air chamber, and means for reciprocating the agitator.
- In testimony whereof, I sign this specification.

PETER F. SCHNEIDER.
